UNITED STATES PATENT OFFICE

161,237

SPORT SHIRT OR THE LIKE

Victor G. Boehlein, Oklahoma City, Okla.

Application May 31, 1949, Serial No. 2,959

Term of patent 14 years

(Cl. D3—25)

To all whom it may concern:

Be it known that I, Victor G. Boehlein, a citizen of the United States, residing at Oklahoma City, in the county of Oklahoma and State of Oklahoma, have invented a new, original, and ornamental Design for a Sport Shirt or the like, of which the following is a specification, reference being had to the accompanying single sheet of drawings, forming part thereof.

Fig. 1 is a front elevational view of a sport shirt, showing my new design; and

Fig. 2 is a rear elevational view thereof.

I claim:

The ornamental design for a sport shirt or the like, as shown.

VICTOR G. BOEHNLEIN.
